Glendale, Calif.

Filed Apr. 15, 1963, Ser. No. 74,443

Term of patent 14 years

(Cl. D81—5)

FIG. 1.

FIG. 2.

FIG. 3.

FIG. 4.

FIGURE 1 is a front elevation of a fire screen incorporating my new design;

FIG. 2 is a top plan view thereof;

FIG. 3 is a side elevational view thereof; and

FIG. 4 is a view similar to FIG. 1 but showing the fire screen in a different adjusted position for purposes of illustrating the appearance of the article when in use.

The dominant features of my design reside in those portions shown in full lines.

The screen mesh pattern which is partially shown in FIGS. 1 and 4 for ease of illustration is understood to cover the entire area within the circular members.

I claim:

The ornamental design for a fire screen or similar article, substantially as shown and described.
